US00D945740S

(12) United States Design Patent (10) Patent No.: US D945,740 S
(45) Date of Patent: * Mar. 15, 2022

(54) APPAREL

(71) Applicant: adidas AG, Herzogenaurach (DE)

(72) Inventors: Dora Szilagyi, Brooklyn, NY (US);
Isabel Hall, Brooklyn, NY (US);
Alexander T. Dichiaro, East
Greenwich, RI (US)

(73) Assignee: adidas AG, Herzogenaurach (DE)

() Term: 15 Years

(21) Appl. No.: 29/714,450

(22) Filed: Nov. 22, 2019

(51) LOC (13) Cl. 24-04

(52) U.S. Cl.

USPC D2/711

(58) Field of Classification Search

USPC D2/700, 701, 705-711, 624
CPC A41C 3/00; A41C 3/04; A41C 3/06; A41C
3/065; A41C 3/144; A41C 3/10
